UNITED STATES PATENT OFFICE.

WILBUR COSS AND WILLIAM STOCKHILL, OF GLASSPORT, PENNSYLVANIA.

CAR-DOOR.

1,260,874.

Specification of Letters Patent. Patented Mar. 26, 1918.

Application filed December 28, 1916. Serial No. 139,288.

To all whom it may concern:

Be it known that we, WILBUR COSS and WILLIAM STOCKHILL, citizens of the United States, residing at Glassport, in the county of Allegheny and State of Pennsylvania, have invented certain new and useful Improvements in Car-Doors, of which the following is a specification.

This invention relates to improvements 10 in car doors and particularly to that type of car doors designed for use on railway freight cars, or for other purposes for which it is found applicable.

An object of this invention is to provide a 15 car door of the type set forth which is permanently supported at its top and bottom whether the door be in a position for closing the car door opening or when shifted to a position at the front or to one side of the 20 opening.

Another object of this invention is to provide a car door of the character described from the outside of which it is impossible to 25 remove the car door hanging devices, thereby preventing access of unauthorized persons to the car, and at the same time establishing a nearly perfect union of the car body and the door, thus providing against the entrance of foreign matter due to climatic conditions.

Further objects of this invention are to provide a car door which is simple in its construction and arrangement, strong, durable and efficient in its use, inexpensive to 35 manufacture and which may be readily opened and closed.

To the accomplishment of these and such other objects as may hereinafter appear, the invention consists of the novel construction, 40 combination and arrangement of parts herein specifically described, and illustrated in the accompanying drawing wherein is shown an embodiment of the invention.

In the drawing forming a portion of this 45 specification and wherein like numerals of reference designate corresponding parts throughout the several views:

Figure 1 is an elevation of the outside of a box car embodying the invention, with the 50 door in open position.

Fig. 2 is a bottom view of Fig. 1, showing the car door supporting devices.

Fig. 3 is a fragmentary perspective view of the car body and the car door, illustrating

the latching device for holding the door in 55 closed position.

Referring more in detail to the drawing, 1 represents the ordinary freight car body provided with the usual side door entrance 2. An outside door 3, slidably supported 60 at the top and base, is arranged to cover the entire door entrance 2.

The hangers, supporting the car door 3 at its upper corners, are in some respects similar to those described in our United States 65 Patent No. 1,154,001, and consist of the integrally formed metallic body portions 4 bent at right angles to form the edge portions 5 and the extensions 6. The extensions 6 are provided with slotted U-shaped 70 portions 7 to form bearings for the rollers 8, the hubs of which normally seat in the apex of the U-shaped portions 7.

Secured to the side of the car body 1 at the top thereof so as to have a portion arranged over the opening 2 and the remaining portion projecting to one side of the opening, is an upper guide-rail 9, which is supported and secured in position by the brackets 10, 11 and 12. The guide-rail 9 is 80 adapted to extend through the slotted U-shaped portions 7 and be engaged by the rollers 8.

The lower corners of the car door 2 are provided with the hanger members 13, consisting of the body portions 14 bent at right angles to form the edge portions 15 and the extensions 16. Adjacent the ends of the extensions 16 are the apertures 17, securely mounted into which is the guide-rod 18, in 90 a manner so that one end of the said guide rod will form the rod projection 19.

The angle bars 20, extending transversely of the outside of the car door 3, are provided to strengthen the door and are secured thereto, by means of the bolts 21 and the nuts 22, which, with the screws 23, also secure the hangers at their respective corners to the car door. The nuts 22 of the bolts 21 are positioned against the angles of 100 the bars 20, thus safeguarding against their removal from the exterior of the freight car.

Securely mounted on the side of the car body 1, at the bottom thereof, are the brackets 24 and 25 provided with the apertures 26 and 27 respectively.

The guide-rod 18, carried by the hanger

members 13, extends through the aperture 26 of the bracket 25, and holds the door permanently supported at its bottom. When the car door 3 is in the closed position, the projection 19, of the guide-rod 18, will engage in the aperture 27 of the bracket 24 and may be locked by passing the key 28 through the aperture 29 in the projection 19, or in any desired manner.

10 The usual stop strips 30 are provided to limit the movement of the car door 3 in either direction.

From the foregoing description, taken in connection with the accompanying drawing, the advantages of the construction and the method of operation will be readily apparent to those skilled in the art to which the invention appertains, and while describing the principle of operation of the invention together with the device which is now considered to be the best embodiment thereof, it is to be understood that the device shown is merely illustrative and that various changes in the form, proportion and the minor details of construction may be resorted to without departing from the prin-

principle or sacrificing any of the advantages of the invention as defined in the appended claim.

What we claim as new and desire to secure by Letters Patent is:—

In combination with a pair of stationary apertured brackets and a car door provided with hanger members, of a guide rod, fixedly supported by the said hanger members, 35 having one end thereof projecting beyond the edge of the said car door and having an aperture formed therein for the reception of a locking element, said guide rod having a 40 slideable connection with one of the said brackets intermediate of the said hanger members and the said projecting end of the guide rod adapted for passage through the aperture in the other of said brackets.

In testimony whereof we affix our signatures in the presence of two witnesses. 45

WILBUR COSS.
WILLIAM STOCKHILL.
